ESTERS OF UNSATURATED POLYHYDROXY ESTRANE

Karl Miescher, Richen, near Basel, and Caesar Scholz, Basel, Switzerland, assignors to Society of Chemical Industry in Basle, Basel, Switzerland

No Drawing. Application July 26, 1937, Serial No. 155,825. In Switzerland July 30, 1936

6 Claims. (Cl. 260—397)

Previously the only aliphatic esters of the unsaturated polyhydroxy-estrane series which have been described in literature were a mono- and a diacetate of estradiol and the triacetate of estriol. It has now been found that aliphatic esters of compounds of the unsaturated polyhydroxy-estrane series, the acid residues of which contain in the case of the mono-esters more than three carbon atoms or in the case of di- or tri-esters together more than four or six carbon atoms, respectively, have a particularly protracted effect which exceeds that of the corresponding acetates. By suitable choice of the acid residues the duration of the effect may be varied within certain limits, which is of great importance for therapeutic purposes.

It is known that the 3-monobenzoate of estradiol has a certain protracted effect. It could however not be anticipated in any way that compounds can be produced according to the present process which considerably surpass the 3-monobenzoate as regards the duration of the effect.

If 25_γ each, for example, of an estradiol ester, dissolved in 0.5 cc. of sesame oil, are injected into female castrated rats, for instance on two consecutive days, and the duration of the estrus by vaginal smears is ascertained, it is found that the 3-monobenzoate, the 17-monoacetate, and the diacetate act only for 15–19 days (the 3-monoacetate even 3 days only). However, the duration of the estrus, for example when using the 17-mono-n-butyrate, is 27 days, in the case of the dipropionate 60 days, in the case of the 3-monocaprinate and the 3-mono-palmitate 76 days, in the case of the divalerate 80 days, in the case of the 3-monostearate 81 days, in the case of the 17-monovalerate 87 days, and in the case of the dicaprinate even 150 days.

The new esters are produced by partial or complete esterification of compounds of the unsaturated polyhydroxy-estrane series with suitable aliphatic acylating agents of the mono-carboxylic acid series.

Similarly substituted di- and tri-esters are obtained in a manner known in itself. 3-monooesters are produced advantageously according to the method of Schotten-Baumann. When working in the absence of alkalies under careful conditions of reaction, one succeeds in obtaining 17-mono-esters or 16, 17-di-esters, particularly when using free acids or anhydrides thereof. By further esterifying the partially esterified compounds with similarly or differently constituted acylating agents, similarly or mixed substituted di- or tri-esters can be produced.

Suitable acylating agents are, for example, the corresponding aliphatic acids themselves or their anhydrides, halides or esters formed with alcohols of low molecular weight (exchange esterification) or also corresponding ketenes. The said ali-

phatic acids may be straight or branched, saturated or unsaturated. Suitable acid components are, for example, propionic acid (in the case of polyesters), butyric acids, crotonic acid, valeric acids, caproic acids, oenanthic acid, caprylic acid, pelargonic acid, capric acid, lauric acid, myristic acid, palmitic acid, stearic acid and the like, further also suitable esters of carbonic acid. Esters with substituted acids, for example, acids containing hydroxyl or halogen, such as lactic acid, are also of interest. In the case of mixed esters one of the acid components may be, for example, formic acid or acetic acid.

By the expression compounds of the unsaturated polyhydroxy-estrane series there are to be understood, for example, estradiol, dihydroequilenine and estriol.

The new compounds are applicable for therapeutic use.

The following examples illustrate the invention, the parts being by weight:

Example 1

A mixture of 2.2 parts of estradiol, 12 parts of pyridine and 9 parts of propionic anhydride is heated for some time at 105° C. After cooling the mass is gradually diluted while shaking with 300 parts of water, whereupon the estradiol di-propionate crystallizes directly. After standing for some time the crystals are filtered off and washed with N-sulfuric acid, water, saturated sodium bicarbonate solution and finally with water. For purification the compound is recrystallized from aqueous methanol. It melts at 104–105° C.

The same compound is obtained by propionylating estradiol 3- or 17-monopropionate of melting point 124.5–125.5° C. and 199–200° C., respectively.

Example 2

A mixture of 2.4 parts of estradiol, 12 parts of pyridine and 10 parts of n-butyric anhydride is heated for some time at 115° C. It is then cooled and mixed while stirring with 250 parts of water, whereupon an oil separates. The latter is extracted with ether and the ethereal solution is washed successively with N-sulfuric acid, water, N-sodium carbonate solution and water. The dried ethereal solution is freed from ether and the residual oil distilled in a high vacuum. The estradiol di-n-butyrate thus obtained may be recrystallized from a mixture of methanol and water. It melts at 64–65° C.

The estradiol di-iso-butyrate of melting point 100.5–101.5° C. is also obtained in quite analogous manner.

Example 3

2.3 parts of estradiol are mixed with 12 parts of pyridine and 10 parts of n-valeric anhydride and the mixture is heated for some time at 115° C. in

the oil bath. The cooled solution is mixed with 250 parts of water, whereupon an oil separates; this is extracted with ether. The separated ethereal solution is washed successively with N-sulfuric acid, water, N-sodium carbonate solution and water and then dried. The ether is then removed and the residue purified by distillation in a high vacuum. The estradiol di-n-valerate forms a yellowish oil.

10 The estradiol di-iso-valerate is also obtained in quite analogous manner.

The reaction may also be carried out in the presence of other tertiary bases, such as for example dimethylaniline, quinoline, and the like, or 15 also without such bases.

Example 4

1.5 parts of estradiol are dissolved in 15 parts of pyridine and mixed while shaking with 4.5 20 parts of capranyl bromide. The mixture is allowed to stand for 12 hours, whereupon it is mixed with

25

and extracted with ether. The ethereal solution is washed successively with N-sulfuric acid, water, N-caustic soda solution, sodium carbonate solution of 10 per cent. strength and then again 30 with water. The dried ethereal solution is concentrated and the residual oil of estradiol di-caprinate is purified by distillation in a high vacuum.

The estradiol dipalmitate of melting point 63- 35 65° C. is obtained in quite analogous manner.

Example 5

To a solution of 1 part of estradiol, 5 parts of pyridine and 20 parts of dioxane there are added 40 gradually 5 parts of ethyl chloroformate and the mixture is allowed to stand for several hours. It is then evaporated to dryness in a vacuum and the residue shaken out with ether and water. The ethereal solution is washed with dilute acid, 45 water, dilute sodium carbonate solution and then again with water, dried and evaporated. By recrystallizing the residue from aqueous alcohol there is obtained the estradiol diethylcarbonate of melting point 138-139° C.

Example 6

1.5 parts of estradiol are dissolved in 500 parts of N-caustic soda solution and mixed while shaking with 6.7 parts of capranyl chloride added in 55 doses. After 20 minutes the mass is extracted with ether and the ethereal solution is washed with N-caustic soda solution and water. After expelling the ether the estradiol 3-monocaprinate is purified by treatment with aqueous methanol. 60 It is obtained in the form of leaflets melting at 60° C.

The estradiol 3-monocaproate or -caprylate may also be obtained in analogous manner.

65

Example 7

A solution of 1.5 parts of estradiol in 500 parts of N-caustic soda solution is mixed while shaking strongly with 4.8 parts of palmityl chloride added in small portions. After $\frac{1}{2}$ hour the mass is 70 acidified while cooling, then extracted with ether and the separated ethereal solution is washed with N-caustic soda solution and water. The ether is then distilled off and the residual estradiol monopalmitate is recrystallized from a mixture 75 of acetone and water. It melts at 70-71° C.

Example 8

A solution of 1.5 parts of estradiol in 500 parts of N-caustic soda solution is mixed while vigorously stirring with a solution of 5.2 parts of stearyl chloride in 5 parts of benzene added in small portions. When the reaction is complete the mass is weakly acidified while cooling and the separated oil extracted with ether. The ethereal solution is washed repeatedly with

8

10

and water and then dried. The residual estradiol 3-monostearate obtained after expelling the solvent forms crystals of melting point 78-79° C. It 15 may be crystallized from acetone.

If estradiol 3-monostearate is caused to react with a propionylating agent, for example, propionic anhydride or propionyl chloride, there is obtained estradiol 3-stearate-17-propionate. In similar manner there is also obtained for example the 17-acetate, the 17-formate, the 17-methylcarbamone of estradiol 3-stearate and the like.

Example 9

If 2.7 parts of estradiol, 12 parts of pyridine and 2 parts of n-butyric anhydride are allowed to stand at room temperature and worked up in the usual manner, the estradiol 17-mono-n-butyrate of melting point 166.5-167° C. is obtained after repeated recrystallization. The same compound is obtained for example by the action of n-butyric acid on estradiol in the heat, the operation being conducted in a closed vessel, if desired. The 17-mono-iso-butyrate of melting point 183-183.5° C. and the 17-mono-n-valerate of melting point 144-144.5° C. as well as similar compounds are obtained in similar manner.

By further esterification it is possible to obtain similarly and differently acylated di-esters of 40 estradiol, such as for example the estradiol 3,17-di-n-valerate, the estradiol 3-acetate-17-n-valate and the like.

Example 10

1 part of estradiol is mixed with 1.3 parts of capric acid and heated in a nitrogen atmosphere for sometime to about 200° C. The mixture is extracted with ether, the ethereal solution is washed with soda solution and water, dried and 50 the solvent expelled. The estradiol 17-mono-caprinate of melting point 112-112.5° C. is obtained from the residue by repeated recrystallization from aqueous methanol.

The esterification with the aid of the free acid 55 described above may also be carried out advantageously in the presence of a condensing agent.

Instead of the above mentioned acid their esters with low alcohols, for example capric acid methyl ester, may also be used for the acylation. 60

Dihydro-equilenine and estradiol may be converted in analogous manner into their corresponding esters, such as for example the dipropionates, the dibutyrate, the propionate-butyrate, the tripropionate, the tributyrate, the tricaprate, 65 and the like.

What we claim is:

1. The aliphatic acylated compounds of the unsaturated polyhydroxy-estrane series, the acid residues of which contain in the case of the 70 mono-esters more than three carbon atoms, in the case of the di-esters together more than four carbon atoms and in the case of the tri-esters together more than six carbon atoms.
2. The aliphatic acylated mono-esters of 75

estradiol, the acid residues of which contain more than three carbon atoms.

than three carbon atoms.

3. The aliphatic acylated di-esters of estradiol, the acid residues of which contain more than four carbon atoms.

4. The estradiol dipropionate of melting point 104-105° C. of the formula

5. The di-alkyl carbonic acid esters of estradiol, the acid residues of which contain more than four carbon atoms.

carbon atoms.
6. The estradiol-di-ethylcarbonate of melting point 138-139° C. of the formula 5
